DISPENSER FOR COLLAPSIBLE TUBES, OR SIMILAR ARTICLE

Edward Thomas Hickey, 243 W. Fox Dale Drive,
Milwaukee, Wis.

Filed Mar. 29, 1962, Ser. No. 69,491

Term of patent 14 years

(Cl. D4—3)

FIGURE 1 is a side elevational view of a dispenser for collapsible tubes, or similar article, showing my new design, the dotted line showing of a tube being for illustrative purposes only, and it being understood that the opposite side of the dispenser presents a mirror image of the illustrated side;

I claim:

The ornamental design for a dispenser for collapsible tubes, or similar article, substantially as shown and described.
